UNITED STATES PATENT OFFICE.

OVIDE ST. MARIE, OF ASTORIA, NEW YORK.

DESIGN FOR A DIE-HOLDER.

42,922.

Specification for Design.

Patented Aug. 20, 1912.

Application filed August 24, 1911. Serial No. 645,846. Term of patent 7 years.

To all whom it may concern:

Be it known that I, OVIDE ST. MARIE, a citizen of the United States, residing at Astoria, in the county of Queens and State of New York, have invented a new, original, and ornamental Design for Die-Holders, of which the following is a specification, reference being had to the accompanying drawing, forming part thereof, in which—

Figure 1 is a perspective view of a die

holder showing my new design. Fig. 2 is a front elevation of the same. Fig. 3 is a side elevation.

I claim:

The ornamental design for a die holder, as shown.

OVIDE ST. MARIE.
